UNITED STATES PATENT OFFICE.

RAMON G. ANTONIO, OF MANILA, PHILIPPINE ISLANDS.

CLIP AND PENCIL FOR FOUNTAIN PENS.

Application filed April 5, 1922. Serial No. 549,867.

This invention relates to new and useful improvements in clips and pencils and particularly to clips and pencils for attachment to fountain-pens.

5 One object of the invention is to provide a clip for a fountain-pen or pencil which has an extensible pencil, and wherein the pencil of the clip is adapted for use by simply removing and reversing the clip on the 10 barrel or cap of the pen or the stem of a pencil.

Another object resides in the novel construction of the lead carrier which is adapted to be locked in extended or withdrawn 15 position and wherein the means for so manipulating the lead is readily accessible.

Other objects and advantages will be apparent from the following description when taken in connection with the accompanying 20 drawing.

In the drawing:

Figure 1 is an elevation of a fountain-pen showing the clip applied thereto, and with the cap of the pen in closed position.

25 Figure 2 is an elevation of the cap removed from the pen and showing the lead extended from the end of the clip in position for writing.

Figure 3 is an enlarged elevation of the 30 clip removed from the cap of the pen, and showing the means for extending and withdrawing the lead.

Figure 4 is an elevation of the lead carrier removed from the clip.

35 Referring particularly to the accompanying drawing, 10 represents a split ring or band which is frictionally engaged around the cap 11 of the fountain-pen 12, adjacent the open end thereof, and with its finger

40 13 extending beyond the said open end of the cap. This finger is longitudinally split, as shown at 14, and is rolled into tubular form, the outer end of the finger being in the form of a ball head 13', with its outer

45 extremity opening into the bore of the tubular portion. The inner end of the finger, or that portion which joins onto the ring or band 10, is widened, as seen at 15, and secured across this widened portion is a

50 small brace 16. The inner end of the split of the finger flares in the direction of the portion 15, and in one side wall of the split, at such flared portion, there is formed a notch 17. In one wall of the split, at a

55 point outwardly of the brace 16, there is

formed another notch 18, said notch being, however, formed in the opposite wall from that in which the notch 17 is formed.

Slidable longitudinally in the tubular portion of the finger is a longitudinally split tube 19, in which is disposed the writing lead 20. In opposite sides of the tube 19 are formed the small openings 21 for the introduction of the point of a pin, or like instrument, to move the lead out, 60 as the writing end thereof becomes worn down. Carried by the inner end of the tube 19, and projecting through the split of the tubular portion of the finger 13, is a small pin 22 which is adapted to be grasped by 65 the user to slide the tube 19 longitudinally in the finger, when extending or withdrawing the lead. This pin 22 is adapted to be moved laterally in the split of the finger, to 70 rotate or rock the tube 19, and be disposed 75 in one or the other of the notches 17 or 18, for the purpose of holding the tube 19 in extended or withdrawn position.

It will be noted that the tube 19, as well 80 as the ball head 13', are resilient and normally closed, or sprung together, with the result that when the tube 19 is slipped outwardly the head 13' will frictionally engage with and press the tube 19 so as to not only maintain the lead firmly in position within the tube, but maintain the tube 85 in writing position in the tubular portion of the finger, and properly extended from the head.

When the lead and tube are withdrawn 90 into the finger of the clip, the clip is capable of performing the usual function of a clip of this character, the finger projecting from the open end of the cap of the pen, onto the adjacent portion of the barrel thereof. When the device is to be used as a pencil, 95 the cap is removed from the barrel of the pen, and the lead slipped out into writing position, the cap being held in the fingers in the manner of the ordinary pencil. The preferred manner of use is, however, to remove the clip and reverse its position on the cap of the fountain-pen, or the stem of 100 a pencil.

The device is very simple in construction, 105 and is composed of few parts, which can be manufactured at a comparatively low cost. Furthermore, the device, when applied to a fountain-pen, serves as a clip and as a pencil, thus providing the owner with both pen 110

and pencil in one instrument, while at the same time the pencil does not interfere with the clip.

What is claimed is:

- 5 As an article of manufacture, a pencil comprising a tubular body having an enlarged outwardly tapering head on one end and a split ring on the other end for attachment to a support, the body being formed
- 10 with a longitudinal slot between the head and split ring, one wall of the slot having lateral notches intermediate its ends, a tapering and longitudinally split pencil head holder slidable and rotatable in the

tubular body and having a finger-piece arranged to be grasped to slide and rotate the holder and for engagement interchangeably in said notches to hold the holder in different positions within the tubular member, the smaller end of the holder being adapted to be wedged in said head whereby to cause the holder to firmly grip the lead while a portion thereof projects beyond the head.

In testimony whereof, I affix my signature.

RAMON G. ANTONIO.
